METHOD OF AND DEVICE FOR COLLECTING
DUST AND FLY, PARTICULARLY IN TEX-
TILE FACTORIES, AS SPINNING MILLSOtto Heinrich Hess, Winterthur, Switzerland, as-
signor to the firm Actiengesellschaft Joh.
Jacob Rieter & Cie. Winterthur, SwitzerlandApplication June 29, 1937, Serial No. 151,002
In Germany July 1, 1936

2 Claims. (Cl. 19—140)

This invention relates to methods of and de-
vices for collecting dust and fly particularly in
textile factories, as spinning mills.

The method according to the invention is dis-
tinguished by starting to carry off the dust and
fly particularly in the immediate vicinity of the
places of development thereof by application of
electrostatically charged bodies.

This provision permits of concomitantly re-
moving dust and fly, in an advantageous manner,
from their places of development in which way
the disadvantages otherwise arising (for exam-
ple, soiling the machines, molesting the attend-
ants or impairing the goods produced, as the
case may be) are avoided.

By means of the method according to the in-
vention dust and fly can be started to be carried
off at the places of development thereof by ac-
tion of an air current and be passed to electro-
statically charged bodies, or bodies adapted to
be electrostatically charged can be arranged in
the immediate vicinity of the places of develop-
ment of dust and fly, or both of these modes of
procedure can be applied to one and the same
source of development of dust and fly. In any
case, rollers may be used as bodies adapted for
being electrostatically charged which can be ren-
dered operative, advantageously, by rotating the
same by means of the working tool to which such
rollers are applied whereby a separate or addi-
tional source of power may be dispensed with.
Advantageously, rollers are used which are made
of materials, as glass, ebonite, press material
etc., that are susceptible to electrostatic charging.
For improving the capacity of the rollers for col-
lecting the foreign matter it is advisable to cover
the rollers with a lagging known per se, as cloth,
felt, plush, velvet or the like. The charging of
the rollers with static electricity may, however,
also be effected by means of a separate source of
electric current.

The accompanying drawing serves for explain-
ing the manner in which the invention as applied
by way of example to a drawing frame is carried
into effect with the aid of rollers adapted to be
electrostatically charged and to some extent also
by means of a gaseous medium. In the drawing

Fig. 1 shows a schematic elevation partly in
section of means for carrying the method ac-
cording to the invention into effect,

Fig. 2 is an axial section of one of the above-
mentioned roller-shaped bodies, and

Fig. 3 is a view similar to Fig. 1 showing modi-
fied means for carrying the method according
to the invention into effect.

Referring to Fig. 1, the side shields of the
drawing frame are designated by A. Numerals
1, 2 and 3 denote the fluted rollers against which
bear the top rollers 4, 5 and 6. Numeral 7 refers
to the spinning material, as cotton, wool or the
like, which passes in a fleece between the fluted
rollers and the top rollers in the direction of
arrow 7a. The fluted rollers 2, 3 are journaled
in bearing pockets B of the shields A and are
maintained clean by a clearer roller 8, which is
journaled in bearings C provided on the shields
A. The rollers 4, 5 which are guided with their
journals in a like manner as the top roller 6 in
guide slots D of the shields A are maintained
clean by a clearer roller 9, whilst the fluted roller
1 which is also journaled in bearing pockets B
is cleaned by a clearer roller 10 which in turn
is journaled in bearings C on the shields A. The
clearer rollers 8, 9 and 10, which turn together
with the associated fluted and top rollers re-
spectively, are hollow and are made of a mate-
rial permitting to be readily electrostatically
charged.

To the outer circumference of the clearer roller
8 a friction rubbing element 11 is correlated,
which is carried on a frame bracket E and the
outer surface of which has a curvature corre-
sponding to that of the said roller circumference
and is provided with a lagging 12 of felt, leather
or the like, the rubbing element 11 being forced
into slight bearing engagement with the roller 8
by suitable means (not shown).

In the interior of the rollers 9 and 10 a rubbing
element 13, consisting of an adequately heavy
material, is stationarily arranged, the rubbing
element provided on its surface curved in con-
formity with the corresponding roller with a lag-
ging 14 of felt, leather or the like. The rubbing
elements 13 bear against the respective rollers
by means of their laggings by action of their
own weight. In the exit of the drawing frame,
a further roller 15, a so-called fancy stripper, is
mounted in a frame bracket F. The roller 15 is
of similar construction as the clearer rollers and
is provided, similarly as the rollers 9, 10, with
an inner freely engaging rubbing element 13 hav-
ing a lagging 14.

During the operation of the drawing frame, as
effected by external power in usual manner, the
rollers 1, 2, 3 turn clockwise and the rollers 4, 5
and 6 anticlockwise, as indicated by the respec-
tive arrows. The clearer rollers 8, 9 and 10 are
turned by frictional circumferential engagement
with these rollers in the directions indicated for
each of the clearer rollers by a further arrow, 55

whereas the clearer roller 15 is driven, for example, through the intermediary of a flexible endless driving means 15a, by the roller 1, in a direction as indicated by the respective arrow. By 5 effect of the turning movements of the clearer rollers during rotation of the rollers 8 to 10 and 15 static electricity is generated by the correlated rubbing elements.

The four rollers 8, 9, 10 and 15 are each provided at the two face ends with a flanged limiting wall 16 of a material which insulates against electricity, as shown in Fig. 2 for roller 10. The limiting walls 16 of these rollers are each provided with a central journal pin 17 for inserting the 15 rollers in suitable bearings as indicated at C.

During the operation a time-lag sets up between the pairs of elements 3, 6 and 2, 5 as well as 1, 4 of the drawing frame, whereby the spinning material 7 is expanded. Incidental thereto individual 20 fibres fly off the spinning material away from the drawing field and at the same time dust and other impurities separate out. These separated particles are attracted and retained within the drawing frame by the circumference of the nearest 25 roller 8, 9 or 10 which have been electrostatically charged by effect of the drive imparted to the drawing frame. Also fly and dust having already passed out of the drawing frame at the delivery end thereof return to the rollers 9, 10 or are 30 attracted and retained by the roller 15. Threads that may have been torn are immediately wound on the fancy stripper 15.

Clearer plates or clearer pallets may be used as electrostatically charged bodies instead of rollers, 35 driving such bodies being dispensable by actuating correlated rubbing elements which serve for producing the electrostatic charging, if desired, by action of the moving drawing frame or else in such manner that rubbers of this kind are arranged directly on moving elements of the drawing 40 frame.

In the modification shown in Fig. 3, means are provided for removing dust and fly by an air current in combination with means of the kind 45 described above.

The drawing frame to which the modified impurity removing means are applied comprises also in this case fluted rollers 1', 2' and 3' and top rollers 4', 5' and 6' all of which are mounted 50 between the side shields A'. The top rollers 4', 5' are again cleaned by a clearer roller 9' associated with a rubbing element 13', whereas the fluted rollers 1', 2' are cleaned by means of a horizontal 55 pressure cylinder 18' cooperating with a clearer roller 8' which is correlated to the roller 3' and has a relatively large circumferential area. The roller 8' is mounted in bearings, (not shown) substantially similar to bearings C of Fig. 1, arranged on the side shields A' and frictionally engages 60 with the circumference of the roller 3'. On the other hand, the circumference of the clearer roller 8' is frictionally engaged by a rubbing element 11 65 stationarily mounted on a frame bracket E'.

The pressure cylinder 18', which is fixed underneath the roller 1' and is provided with an elong-

ated nozzle 19' extending parallel with the axis of the cylinder across the shell of the latter, is supplied with compressed air, through a pipe connection 20'. The nozzle 19' is so arranged near the top of the cylinder 18' on the side of the latter 5 facing the clearer roller 8' that the current of air emanating from the nozzle during the operation of the drawing frame flows substantially horizontally across the undersides of the fluted rollers 1', 2' over to the clearer roller 8' as indicated by 10 arrows 21'. At the same time the rollers 1' to 6' and 8', 9' rotate in the directions as indicated by the respective arrows, so that static electricity is generated at the rubbing elements 11' and 13'. Consequently the rollers 8' and 9' are electrostatically charged, as explained above. Alternatively, the electrostatic charging of the roller 8' may be effected with the aid of a rubbing element arranged in the hollow interior of the roller, and, instead of a roller an electrostatically charged 20 plate or the like may be provided.

The foreign matter adhering to the circumferences of the rollers 1', 2' is carried off by the air current 21' and is attracted by the electrostatically charged surface of the roller 8', when the air 25 current comes within the range of operation of this surface, and is then attracted and retained by the latter.

It is also feasible to employ rollers, plates or similar bodies which are electrostatically charged 30 by a separate source of electricity in such manner that an attractive power obtains as required for the intended purpose.

I do not limit myself to the particular size, shape, number or arrangement of parts as shown 35 and described, all of which may be varied without going beyond the scope of my invention as shown, described and claimed.

What I claim is:

1. Method of precipitating dust and flying particles in drawing machines comprising electrostatically charging a cleaning roller contacting the periphery of a drawing roller of the drawing machine and driven thereby, so that the dust and flying particles are attracted and retained, directly 45 adjacent a point at which they arise, and blowing dust and flying fibers from other points of the drawing machine at which they arise into the effective field of the electrostatically charged cleaning roller.

2. Arrangement for collecting dust and flying fibers from textile drawing machines having rollers, and like machines, comprising a cleaning roller of a material which is readily charged electrostatically, said cleaning roller contacting a 55 roller of the drawing machine or the like, a rubbing element contacting said cleaning roller to charge it electrostatically, and means for directing air currents from other portions of the drawing machine into the vicinity of the cleaning roller, so that said cleaning roller electrostatically 60 attracts and retains flying dust and fibers directly at the location where said flying material is caused.

OTTO HEINRICH HESS.
